MACHINE FOR AND METHOD OF MAKING
PAPER CUPSLouis V. Lucia, West Hartford, Conn., assignor to
Lucup Corporation, a corporation of New
York

Application November 8, 1935, Serial No. 48,820

27 Claims. (CL 93—36.05)

This invention relates to a novel method and machine for making tapered paper cups from a web of paper.

In the manufacture of cups of this type, by the methods now commonly used, it is necessary to first cut the blanks for the cups from a stack of sheets by means of a die in a heavy press. The blanks are then stacked upon a machine and fed individually thereto by an air operated feeding device. Such feeding devices are inherently troublesome and the feeding of the blanks to the machine is affected by atmospheric conditions which frequently create static to such an extent that it will interfere with the feeding operation and also with the operation of the machine itself.

The object of this invention, therefore, is to provide a machine which will produce a cup of this type at a high rate of speed and also with a minimum of labor by eliminating the operation of cutting the cup blanks from a stack of paper as now commonly done.

A further object of the invention is to provide a machine for cutting a blank of correct form, from a web of paper, and to produce a tapered cup therefrom with a minimum of waste in material.

A still further object is to include, in a machine for making paper cups, a means for arranging the finished cups upon their delivery either in a nested or stacked order.

The means by which the above objects may be obtained are fully illustrated in the accompanying drawings in which:

Figure 1 is a plan view in elevation of my improved machine.

Figure 2 is a similar view of the continuation thereof on line 2—2 of Figure 1.

Figure 3 is a fragmentary view illustrating a modification in the blank cutting mechanism which will produce a blank of slightly different form for a cup of modified form.

Figure 4 is a view, in central vertical section, on line 4—4 of Figure 1.

Figure 5 is a fragmentary view illustrating a modified form of construction at the delivery end of the machine for delivering the cups in a stacked arrangement.

Figure 6 is a plan view, in elevation, of the gumming mechanism shown in Figure 4.

Figure 7 is a detailed view of a pair of rollers used in the machine.

Figure 8 is a detailed view of the creasing rollers.

Figure 9 is an enlarged view, in central ver-

tical section, illustrating the operating of the various rollers of the machine in forming a cup.

Figure 10 is a view, in central vertical section, of the web feeding end of the machine.

Figure 11 is a fragmentary view illustrating a gumming device for applying gum to the said web.

Figure 12 is a fragmentary plan view, in elevation, illustrating the blank cutting mechanism.

Figure 13 is a plan view of a cup blank as cut from the web.

Figure 14 is a view showing the said blank after the first folding operation.

Figure 15 is a bottom edge view thereof.

Figure 16 is a top edge view thereof.

Figure 17 is a view showing the said blank 15 folded into a completed cup.

Figure 18 is a view showing the modified type of cup produced by the modification illustrated in Figure 3.

As illustrated in the drawings, the numeral 5 20 denotes a frame comprising side members 6—6 having, at one end thereof, diagonal extensions 7—7 on which are mounted a pair of hangers 8—8 to support a roll of paper web 9 on a spindle 10. The said web travels over a web supporting roll 11 mounted upon the said extensions. A web supply roller 12, having a tire 13 of rubber or other suitable material, is rotatably mounted on a shaft 14 in a bearing 15 on the end of a bar 16 which is hinged to the shaft 11. A pulley 18 30 is connected to said shaft 14 for rotating the roller 12. A belt 19 extends over the said pulley and over the driving pulley 20 which is connected to the said shaft 11.

The said web passes over a guide roll 21, 35 mounted in the extensions 7—7, between guide bars 22—22 on a plate 23 that is supported on said extensions, and over a feed roll 24 which preferably has a resilient covering 25. Web retaining spring members 26—26 are mounted on a supporting bar 27 and are in frictional engagement with the web 9. Web holding strips 28—28 are mounted on a supporting bar 29 for holding the end of said web in position.

A pair of interrupted web feed rolls 30—30 are 45 mounted on a shaft 31 which is located directly over the feed roll 24 and rotatable in slide blocks 31a. These blocks are slidably mounted between posts 31b and are forced downwardly by springs 32 to cause engagement of the feed rolls 30—30 50 with the web. Each of said blocks has a stop lug 32a which engages the bottom of the slide to space the feed rolls from the web during the passage of the cutaway portion 33 thereover. The rolls 30—30 are provided with a feeding cir- 55

cumferential surface 33a of a length equal to the length of web which is to be fed by the said feeding rolls at each rotation thereof.

A gumming disc 34 is also mounted on the said shaft 31 for applying a strip 35 of adhesive, such as gum, near the edge of said web during its passage through the said feed rolls. This disc 34 is suitably cut away for spacing the said gum strips and also to disengage the said web at the time that it is released by the feed rolls 30-30.

A cutting-off device, in the form of a punch 36, is mounted on a carrier 37 vertically slidable upon posts 38-38 which are mounted on a die plate 39 that has an opening 40 therein adapted to receive the punch 36 with the cutting edges 41 and 42 in shearing contact with the cutting edges of said punch. The said punch is moved in a downward direction by means of a cam 43 which is mounted upon the shaft 31 to trip a lever 44 secured to a rock shaft 45 to which is also secured a punch operating lever 46 that is connected to said slide 37 by a pair of links 47 by means of hinged pins 48-48.

The said punch is moved in an upward direction by means of a cam 49 which rocks a lever 50 that is also secured to said rock shaft 45.

The end of the web 9 comes to a stop upon the plate 39 and is cut off by the punch 36 in the shape of a blank 51 which rests between a pair of creasing rolls comprising a lower roll 52 that is provided with a covering 52a of resilient material, such as rubber, and mounted upon a shaft 53 rotatable in the side members 6-6 and an upper creasing roll 54 which is mounted on a shaft 55 rotatable in a pair of slide blocks 56 slidably supported between upright posts 57 on the side members 6-6. The said upper creasing roll 54 is provided with a pair of diverging creasing blades 58 and is cut away as at 59 to provide a clearance between the said creasing rolls during a portion of their rotation. The said creasing roll 54 is forced downwardly into contact with the lower creasing roll 52 by means of springs 60 acting upon the slide blocks 56 which are provided with stop lugs 61 adapted to engage with the bottom of the slides in the extensions 57 and support the creasing roll 54 in out-of-contact position with respect to the lower creasing roll 52 during the passage of said cut away portion thereabove. A guard disk 54a is mounted on said shaft 55 for the purpose hereinafter described.

A blank holding shoe 62 is provided for holding the end of the web upon the die plate 39 while the said end is being cut off into the blank 51 by the punch 36. This shoe is mounted, by means of a lever 63, upon a rock shaft 64 which is rocked in one direction by a spring 65 to force said shoe downwardly upon said blank. A lever 66 is also secured on said rock shaft 64 and operated by a cam 67 mounted upon the shaft 55 to lift said shoe 62 from said blank.

A feed roll 68 is mounted between the side members 6-6 on a shaft 69 and a pressure roll 70 is mounted thereabove, and in contact therewith, on a bar 71 which is supported on slide blocks 72 that are slidably mounted between the extensions 73 and forced downwardly by a pair of springs 74.

A guide bar 75, having upturned side portions 75a and an opening 75b through which the roll 70 projects, is supported by means of a bracket 76, upon a supporting bar 77. This bar is mounted on the supporting plate 78 which rests upon

the side members 6-6 and has an opening 79 through which the roll 68 projects.

At the sides of said guide bar 75 are provided folding fingers 80, 81, 82, and 83 which are also mounted upon said plate 78.

A pair of creasing and pressing rolls, are also provided, which comprise a lower roll 84 mounted upon a shaft 85 that is rotatable in the side members 6-6 and an upper roll 86 mounted upon the shaft 87 rotatable in slide blocks 88 which are slidably mounted between posts 89 and forced downwardly by a pair of springs 90. The said roll 84 has a creasing groove 91 into which fits a creasing blade 92 mounted in the upper roll 86.

Each of said rolls 84 and 86 are provided with corresponding diverging grooves 84a and 86a for the purpose hereinafter described.

A pair of transfer rolls are provided, comprising a lower roll 93 mounted on a shaft 93a, between the side members 6-6, and an upper roll 94 mounted on a shaft 94a which is rotatable in a pair of slide blocks 95 that are slidably mounted between posts 96 and pressed downwardly by a pair of springs which are not shown. Each of said rolls 94 and 93 is also provided with corresponding diverging grooves 93b and 94b. The upper roll 94 is cut away in its center to provide a circumferential recess 97 in which is mounted a gumming pad 98. A plate 99 is provided between the said sets of rolls and mounted on the said side members 6-6. A similar plate 100 is mounted between said side members following the said transfer rolls. A pair of shoes 101 are mounted on said plate 100, spaced therefrom and supported thereon by means of a bar 102 on which is also mounted, between said shoes, a folding finger 103 having a guide extension 104 positioned below said bar and also spaced from the plate 100.

Another pair of pressing rolls comprise an upper roll 105 mounted on a shaft 106 which is rotatable in a pair of blocks 107 that are slidably between posts 108 and pressed downwardly by springs 109, and a lower roll 110 mounted upon a shaft 110a that is rotatable in the side members 6-6. The said rolls are also provided with corresponding diverging grooves 105a and 110b.

A trough 111 is mounted upon a bar 112 between the side members 6-6 and following the said rolls 105 and 110. If desired a trough 111a, of a slightly modified form such as shown in Figure 5, may be substituted for the trough 111 to accomplish the purpose to be hereinafter described.

A driving pulley 113, which may be driven by any suitable source of power, is connected preferably to one of the roll shafts such as the shaft 96a. The entire machine is driven by means of this pulley through a system of gears and pinions which interconnect the rotatable shafts, as clearly illustrated in Figure 1, on which the various rolls are mounted. It will be noted that the shaft 17 is disposed diagonally at an angle of substantially 45° to the shaft 53 by which it is driven through a pair of spiral gears 114. Each set of upper and lower rolls are geared together so that they will rotate in opposite directions in order to move a blank in one direction through the machine.

It will also be noted, from Figure 4 of the drawings, that a gumming device is provided to apply gum to the pad 98 on the shaft 93a. This gumming device consists of a gum container 115 mounted upon a frame 116 which is supported on

5 a bar 111. A gumming roll 118 is rotatably mounted in said frame and extends into the gum in the container 115. A gum transfer roll 119 is also mounted in said frame in contact with the said gumming roll and a second gum transfer roll 120 which is mounted on a shaft 121 that is rotatably mounted in the end of the said frame. A pair of driving discs 122 are also mounted upon the shaft 121. These driving discs rest upon the 10 transfer rolls 94 and are driven thereby in order to rotate the gum transfer roll 120, and through a train of gears 123, also said rolls 120, 119, and 118. A gum scraper 124 is mounted upon the frame 115 and rests in contact with the gum roll 118 to scrape the surplus gum off the said roll during its rotation. It will be noted that the gum roll 118 is longer than the transfer roll 119 which in turn is longer than the transfer roll 120 for the following purpose.

20 The gum is picked up from the container by the roll 118 and applied to the roll 119 from which it is picked up by the transfer roll 120 and applied to the gumming pad 98 as it passes under said roll and contacts therewith. The surplus 25 gum on the transfer roll 120 will move off the ends of the roll 120 and accumulate upon the overlapping ends of the roll 119. The surplus gum on this roll 119 will likewise move off its ends on to the overlapping ends of the gumming 30 roll 118 whereby the said surplus gum is returned into the container.

35 A separate gumming device is provided at the feeding end of the machine which consists of a gum container 125 having mounted thereon a gumming roll 126 and a scraper 127 in contact therewith. This gumming device is removably mounted upon the supporting bars 27 and 29 and retained thereon, against longitudinal movement, by means of a notch 127a in the bottom of the 40 scraper supporting posts 128 into which the supporting bar 27 fits.

An air pump 129 is mounted upon the side of the machine and operated through a pitman 130 by means of a crank 131 which is connected to one of the roll shafts. An air nozzle 132 extends from the end of said pump and is positioned adjacent to the web cutting opening 40.

The operation of my improved machine and the method of making paper cups therein are as follows:

50 A roll of paper web 9 is mounted on the hangers 8-8, by means of the spindle 10, and passed over the supporting roll 11 and guide roll 21 so that a portion of said web will hang loosely below the roll 9 in the manner clearly shown in Figure 10 of the drawings. The end of the web is then pushed through the feed rolls 24 and 30-30 and the machine is operated by hand to cause the punch 36 to cut a small piece of the web off the end thereof and form the front part of the blank 60 along the edge 42 of the die.

65 The gumming devices, shown in Figures 6 and 11, are then placed in position and the machine is started in operation. The weight of the bar 16 will serve to keep the web roller 12 in driving contact with the web on the roll 11, which is loosely mounted, and rotation of the said roller 12, by means of the belt 19 from the pulley 20 on the shaft 17, will unwind the web from the roll with a continuous motion at a speed equal to that at which the said web is fed through the machine; thus maintaining the loose portion of web above described in order to eliminate uneven resistance to the pulling of the web by the feed rolls.

70 The feed rolls 30-30 will, during their rotation, cause the said web to be engaged between the surface of the roll covering 25 and the circumferential feed surfaces 33a, thus moving the end of said web forwardly to the position occupied by the blank 51 and at the same time applying a strip of gum 35 to the edge of the web by means of the gumming disc 34 which receives the said gum from the gum roll 126. At this time the cam 67, on the shaft 55, will permit the spring 65 to force the shoe 62 downwardly upon the said end of the web. The cam 43 will then move the lever 44, rock the shaft 45 and force the punch 36 downwardly, by means of the lever 46, cutting off the end of said blank on the edges 41 and 42 and thus forming the blank 51. At this time the air pump 129 is operated, by means of the crank 131, to force a blow of air through the nozzle 132 so as to blow the piece of web, which is cut off, through the opening 40 and into a receptacle 15 which may be conveniently placed under the machine.

20 The shoe 62 is now lifted by the cam 43 and the creasing roll 54 will engage the end of the blank 51, between the creasing edges 58 and 25 the surface of the roll cover 52a, moving the blank forward and at the same time creasing the same on lines, as indicated by the dotted lines 51a in Figure 13, which diverge from the theoretical point 51b located off said blank on 30 the axis thereof.

It will be noted, from the illustration in Figure 8, that the creasing edges 58 will force the blank into the resilient covering 52a of the roll 52; thus definitely forming creases in the said blank 35 without cutting through it.

During this creasing operation, the sides of the blank will move upwardly but, that side on which the gum strip 35 is contained will be held away from the shaft 55 by means of the guard 40 54a in order to prevent the said gum from touching the shaft.

The travel of said blank will be continued, by said creasing rolls, over the plate 78 and under the guide bar 75 until it is engaged between the rolls 68 and 70 by which it is then moved forwardly. While the said blank is being moved by the said rolls 68 and 70, the edges thereof will be engaged by the folding fingers 80 and 82 which will start to fold over said edges on the 50 creases formed by the said creasing rolls. The finger 80 will fold the ungummed side a little ahead of the gummed side of said blank which is folded over it by the finger 82. The forward travel of the said blank will be continued by the 55 said rolls 68 and 70 by which it is pushed under the folding fingers 81 and 83 which will fold the said sides further, and into a position one upon the other, and guide the said partly folded blank between the pressing and creasing rolls 84 and 60 86. The said rolls will then grasp the end of the blank and continue its forward travel. The 65 creasing blade 92 on the roll 86, co-acting with the groove 91 on the roll 84, will crease the partly folded blank on the dotted line 51c, indicated in Figure 14, while the surfaces of said rolls will squeeze the two sides of the blank upon the central portion thereof, as shown in Figure 7 of the drawings, causing the said two sides to be adhered together by means of the gum 35. The 70 said crease, on the dotted line 51c, will cause the end 51d of said blank to assume an upward position as clearly indicated in dotted lines in Figure 9. The travel of said blank is continued by said creasing rolls and the 75

said upwardly extending end of the blank will move through the clearance 97 in the roll 94 and past the gumming pad 98, as clearly shown in dotted lines in Figure 9. The said pad, having 5 picked gum off the gumming roll 120, will deposit the said gum upon the said partly folded blank directly in back of the crease as indicated at 133 in Figure 14. At the same time the said partly folded blank will be engaged by the transfer and pressing rolls 93 and 94 and its forward 10 travel continued thereby. The said blank will then pass under the shoes 101 which will engage the sides of the blank to hold the same downwardly upon the plate 100. The said upwardly extending end 51d of the blank will move 15 between the said shoes and strike the folding finger 103. The said finger will cause the said end of the blank to be folded backwardly upon the gum 133 during the passage of the blank thereunder. The guide 104 will guide the said end 20 between the pressing rolls 105 and 110 which rolls will then press the said end 133 upon the partly folded blank to cause it to be adhered in position thereon and move the said blank, which 25 is now in the form of a completed cup, forwardly and deliver the same upon the trough 111. As clearly illustrated in Figure 4, this trough is so disposed, with respect to the creasing rolls 105 and 110, that it will hold the finished 30 cups in a position whereby they will be received, as they are delivered upon the trough, one within the other in a nested form. The said trough may be made of a width suitable to slightly squeeze the sides of the cup together so as to 35 partly open the cups as they are delivered upon the said trough and thereby facilitate the reception of the cup coming through the rolls into the preceding cup which is already in the trough.

When it is desired to have the cups delivered 40 from the machine in stacked arrangement, the trough may be shaped as illustrated in Figure 5 in which the trough 111a is provided with an upturned portion adjacent to the rolls 105 and 110. This upturned portion will tend to lift the 45 end of the cup, as it is delivered from the rolls, so that the following cup will slide underneath it; thus the cups are delivered into the trough one under the other. The said trough may be made of a suitable length and the sides thereof 50 raised gradually in a direction towards its end so that the cups, as they are pushed forward by their delivery from the machine, will also be lifted into a substantially upright position and one behind the other as clearly illustrated in the 55 said Figure 5.

For the purpose of aiding in the dispensation of the cups, it is preferred not to sharply fold the edges thereof for their entire length, but to fold the upper portion of said edges into what 60 may be termed as a rolled edge. This is accomplished by the method clearly illustrated in Figure 7 from which it may be seen that the edges of the cup register with the diverging grooves 84a and 86a which will allow the folds of the 65 said edges to remain in a slightly extended position while the central portion of the cup is squeezed together by the rolls.

My improved machine may be constructed, as 70 illustrated in Figure 3, to produce a cup of slightly modified form such as that illustrated in Figure 18. In this construction, the cut-off punch and die is made of a slightly different shape so that the corner of the blank is not cut off with the waste portion; thus producing the 75 blank 134 shown in Figure 3, which is of the

slightly different form as compared to the blank 51. In this modification, the creasing edges 58 on the creasing roll 54 are diverged on a slightly different angle so that they will crease the blanks on dotted lines 135. The said blank is folded by 5 the machine in the same manner as the blank 51, with the result that a cup of the form shown in Figure 8 of the drawings will be produced instead of the cup as shown in Figure 17.

While I have illustrated and described a machine of the construction shown in the drawings for producing the said cups, it is to be understood that, if desired, this machine may be further modified in its construction without departing from the scope of my invention. For 15 instance, a set of cutting rolls may be used, instead of the cut-off device illustrated in Figures 10 and 12, so that the web is cut as it passes through the said cutting rolls without requiring an intermittent movement thereof. 20

It is also pointed out that the primary object of my invention, which is to produce a cup of the tapered type from a web with a minimum of waste, is accomplished by disposing the mechanism for feeding the web 9 diagonally and at 25 an angle of approximately 45° to the axis of that portion of the machine which comprises the folding mechanism.

Thus a blank which is substantially square in shape, with the exception that it may have either 30 one or two corners thereof cut off, is produced for such a cup by a simple cutting operation and with a minimum of waste; the said blank being disposed, with relation to the said machine, so that it will be folded thereby on lines diverging 35 from its axis, which axis extends diagonally through said blank.

I claim:

1. In a machine of the character described for forming paper cups from a web, a mechanism 40 for feeding said web to said machine, a cutting-off device for removing a section from said web and thereby producing a cup blank from the end thereof, and a folding mechanism adapted to move said blank through said machine on a plane 45 with said cutting device and in a direction that is diagonally to the axis of said web and during said movement fold the said blank to form a cup therefrom.

2. In a machine for producing paper cups of 50 the character described from a web, a feeding mechanism, a folding mechanism, said feeding mechanism comprising means for feeding the end of said web at an angle to the axis of said folding mechanism, means for removing a single 55 waste portion of said web at a distance from its end and thereby cutting off the said end and completely forming a cup blank having its axis extending at an angle to the axis of said web and disposed in the direction of travel of the 60 said folding mechanism, and means in the said folding mechanism for creasing the said blanks on lines diverging and at an angle to the axis thereof and folding the said blank at the said creases.

3. A machine for producing a cup of the character described from a web; said machine comprising means for feeding the said web to said machine, single means for cutting off the end of said web and thereby completely forming a cup blank, and a mechanism for moving the said blank in a direction at an angle to the axis of said web and on a plane therewith and folding said blank during said movement. 65

4. In a machine of the character described for 70

75

- producing cups from a web, means for feeding the end of said web to said machine, a device for cutting off the end of said web and thereby forming a cup blank upon said machine with its axis angularly disposed with relation to the axis of said web, folding mechanism comprising a plurality of rolls for moving said blank through said machine in the direction of its axis, means for partly folding said blank with its side portions in overlapping position upon the central portion thereof, means for folding the forward portion of said partly folded blank upon the said overlapping sides and thereby complete the folding of said blank into a cup, and pressure rolls for pressing the folded portions of said blank into forceful contact upon each other, said pressure rolls having grooves in the surfaces thereof to prevent pressure upon the folds forming the side edges of said cup.
5. In a machine of the character described for producing cups from a web, means for feeding the end of said web to said machine, a device for cutting off the end of said web and thereby forming a cup blank on said machine, mechanism for partly folding said blank into a tapered form while moving the same through said machine, means for creasing said partly folded blank transversely to its axis and continuing the movement of said blank, and a stationary finger positioned to engage the point of said partly folded blank during the said movement thereof and fold the same at said transverse crease to complete said cup.
6. In a machine of the character described for producing paper cups from a blank, folding mechanism adapted to move said blank through said machine and comprising a creasing roll for creasing said blank on lines at an angle to its axis, means for partly folding the same on said lines into a tapered form, means for positioning the forward end of said partly folded blank at an angle to the adjacent portion thereof, a stationary member positioned to intercept the said forward end during its movement past the said member and fold the same upon said adjacent portion, and means adapted to guide the said adjacent portion in the course of its movement during the folding of said forward end.
7. In a machine of the character described for producing cups from a web, a bed, a device for cutting off the end of said web and thereby forming a cup blank upon said bed with its axis disposed at an angle to the axis of said web, a folding mechanism comprising a plurality of pairs of rolls adapted to engage said blank therebetween and move the same in the direction of its axis upon said bed and during said movement fold the said blank into a tapered cup; said mechanism and rolls comprising a pair of creasing rolls adapted to crease said blank on lines angularly disposed with relation to its axis, means for partly folding the said blank on said lines with its sides in overlapping position upon the central portion thereof, a pair of pressing and creasing rolls for transversely creasing said partly folded blank and pressing the said overlapping sides into contact with each other, a stationary folding member spaced from said bed and in position to be engaged by the forward end of said partly folded blank during its movement thereunder and thereby fold the said end upon the said overlapping sides at said transverse crease, stationary retaining members spaced from said bed and adapted to guide the adjacent portion of said partly folded blank in its movement with relation to said bed while moving thereon during the folding of said end, and a pair of pressing rolls for forcing the said folded end into contact upon said overlapping sides to complete said cup.
8. In a machine for forming paper cups from a blank of sheet material, a folding mechanism comprising a plurality of pairs of rolls for creasing said blank, means for folding the same into a completed cup, and cup supporting means adapted to receive and support the said cups in a position wherein they are nested one partly within the other as they are delivered from the machine.
9. In a machine for forming paper cups from a blank of sheet material, a folding mechanism comprising a plurality of pairs of rolls for creasing said blank and means for folding the same into a completed cup, a trough positioned to receive said completed cups as they are delivered from said machine, and means associated with said trough for tipping the last cup received on said trough in a position whereby its end is disposed to guide the following cup underneath the same and thereby arranging said cups one under the other in overlapping position; said trough having diverging sides gradually straightening and increasing in height towards the end of said trough whereby the said cups will be raised towards the perpendicular and in stacked arrangement as they accumulate and move forwardly in said trough.
10. A machine for making paper cups of the character described from a paper blank, folding means for partly folding said blank into a tapered form while moving on a line of travel, means for transversely creasing said partly folded blank and causing the forward portion thereof to be spaced from said line and a stationary member adapted to engage said forward end and fold the same on said transverse crease during the movement of said blank.
11. A machine of the character described for producing cups from a web; said machine comprising means for feeding the end of said web thereto, means for cutting off a portion of said web and thereby forming a cup blank, means for moving said blank on said machine with its axis disposed at an angle to the axis of said web and on a plane with said feeding means, means for creasing said blank on lines diverging with relation to its axis while moving the same in the direction of said axis, folding means for folding the side portions of said blank on said creases in overlapping position of the central portion thereof, means for creasing the said blank transversely to its axis, and separate folding means for folding the forward portion of said partly folded blank at the transverse crease.
12. A machine of the character described for producing cups from a web, means for feeding the end of said web to said machine, a device for cutting off a portion from said end and thereby forming a cup blank upon said machine, a plurality of rolls for moving said blank through said machine in the direction of its axis, means for first folding two corner portions of said blank upon the central portion thereof, means for folding another corner of said partly folded blank, together with a portion of the said two corner portions first folded upon the same to complete a cup, and means for applying adhesive to said blank for securing the same in cup form.
13. In a machine for making paper cups from a blank of sheet material, a mechanism for folding the said blank into a completed cup, an inclined trough positioned to receive said com-

pleted cups as they are delivered from said machine; said trough having sides adapted to raise said cups from a horizontal to a substantially vertical position and cause the same to be arranged in stacked position as they accumulate upon and move forwardly in said trough.

14. In combination with a machine for making paper cups of the character described from a web of paper, means for cutting off a portion 10 of the end of said web to form a cup blank therefrom, means comprising feed rolls for feeding the end of said web to said cutting means and means co-axial with said feed rolls for applying adhesive to said end of the web before the same 15 is cut off into a cup blank.

15. In a machine of the character described for making paper containers from a web of paper; a folding mechanism comprising a pair of interrupted rolls, a feeding mechanism for 20 feeding the end of said web to said folding mechanism, a cutting device adapted to cut off the end of said web to form a container blank therefrom, and a table on which said blank rests during the cutting operation; said table being disposed in a position whereby the said blank is supported with the forward portion thereof in 25 position to be grasped by the said interrupted rolls upon completion of the cutting operation.

16. In a machine of the character described for 30 forming paper cups from a web of paper, a folding mechanism comprising a plurality of rolls including a pair of creasing rolls at the forward end of said folding mechanism, a feeding mechanism adapted to feed the end of a web of paper 35 to said folding mechanism in position to be engaged by said creasing rolls during the rotation thereof, and a cutting device adapted to cut off the end of said web to form a cup blank therefrom while in position to be engaged by said creasing rolls; the said creasing rolls being cut away 40 to prevent engagement of said blank while the same is being cut off from said blank.

17. In a machine of the character described for 45 forming paper cups from a web of paper; a folding mechanism comprising a plurality of rolls including a pair of creasing rolls at the forward end of said folding mechanism, a feeding mechanism adapted to feed the end of a web of paper to 50 said folding mechanism in position to be engaged by said creasing rolls; a table on which said end is supported during the cutting off operation, and means for clamping said end upon said table while the same is being cut off from said blank.

55 18. A machine for making cups of the character described from a web of paper comprising a folding mechanism, a feeding mechanism comprising a pair of rotatable shafts, feed rolls on said shafts for feeding the end of said web to 60 said folding mechanism, a vertically movable reciprocating cutting device for cutting off the end of said web in the form of a cup blank and means on said rotatable shafts for operating said cutting device.

65 19. A machine for making cups of the character described from a web of paper comprising a folding mechanism, a feeding mechanism for feeding the end of said blank to said folding mechanism, said feeding mechanism comprising 70 a bed, a cutting die mounted on said bed and comprising a vertically movable reciprocating member adapted to cut off a portion of said web near the end thereof and projecting said cut off portion through said bed, a pair of feed rolls in 75 said feeding mechanism for intermittently mov-

ing said web through said cutting device, a pair of rotatable shafts on which said feed rolls are mounted and means on said shafts for directly operating the said cutting device in synchronism with said feed rolls.

20. A machine for making cups of the character described from a web comprising a folding mechanism, a feeding mechanism for feeding the end of said web to said mechanism in position to be engaged thereby, a cutting device positioned between said feeding and folding mechanisms for cutting off the end of said web in the form of a cup blank prior to the delivery thereof to the said folding mechanism; said cutting device comprising a female member on a plane 15 with said feeding mechanism, guide members, a male cutting member reciprocally movable on said guide members and adapted to cut off a portion of said web and project the same through the female member of said device, a pair of 20 rotatable shafts in said feeding mechanism, feed rolls on said shafts and means on said shafts for directly operating the said male member of the said cutting device.

21. A machine of the character described for 25 making paper containers from a web of paper comprising a folding mechanism, a feeding mechanism comprising a pair of rotatable shafts, feed rolls on said shafts for intermittently feeding the end of said web to said folding mechanism, 30 a cutting die for cutting off the end of said web into the form of a container blank, and means operable by said rotatable shafts for continuously drawing said web from a roll thereof and maintaining a slack in said web between the intermittently moving portion thereof and that portion which is continuously drawn from the said roll.

22. In a machine of the character described for 40 making cups from a web of paper, a folding mechanism, a feeding mechanism for feeding the end of said web in position to be engaged by said folding mechanism, said feeding mechanism comprising a frame, feed shafts mounted on said frame, feed rolls on said shafts for feeding said 45 web, and a cutting device removably mounted as a complete unit upon said frame; said cutting device comprising a bed forming the base thereof, a female die mounted on said base, vertical members on said base, a vertically movable reciprocating male cutting member movable upon said vertical members, and means upon said rotatable shafts for directly operating the said male member of the cutting device in synchronism with said feed rolls.

55 23. A machine of the character described for 60 producing cups from a web, means for feeding the end of said web to said machine, means for cutting off a portion from said web and thereby forming a cup blank upon said machine, a plurality of rolls for moving said blank through said machines in the direction of its axis, means for partly folding said blank by folding the two corner portions thereof upon its central portion, means for applying adhesive upon said partly 65 folded blank at a point spaced from the forward end thereof and folding means for folding the said forward end transversely back upon the same and said adhesive.

70 24. A machine of the character described for 70 producing cups from a web; the said machine comprising a folding mechanism, means for feeding the end of said web to said folding mechanism, a cutting device for cutting off the said end into a cup blank; the said folding mechanism 75

- comprising means for folding the side portion of said blank in overlapping position on the central portion thereof, means for creasing the said partly folded blank transversely at points spaced from the forward portion thereof, means for applying adhesive back of said transverse crease and folding means for folding the said forward portion upon said partly folded blank and into contact with said adhesive.
- 5 25. In a machine for producing paper containers of the character described from a web of paper, a mechanism for feeding the end of said web to said machine, means for cutting off the end of said web and thereby forming a container blank, 10 folding mechanism comprising means for partly folding the said blank by folding the side portions thereof in overlapping position upon the central portion of said blank on lines diverging from the axis of said central portion, means for forming a 15 crease upon the said partly folded blank on a line extending across the overlapping area of said side portions, and separate means for folding the said partly folded blank on said crease.
- 20 26. In a machine for making paper containers of the character described, the method for stacking the said containers which consists of delivering them substantially horizontally upon a surface and beneath the preceding containers, moving them forwardly on said surface to accumulate them thereon and thereby permit them to gradually rise to a substantially vertical position.
- 5 27. In a machine for converting a web of paper into receptacles of the character described, 10 the combination of means for feeding the said web lengthwise into said machine, a cutter for cutting off a section of said web, at the end thereof, and thereby forming a receptacle blank therefrom, means for holding said section against 15 movement while it is being cut off from said web, and folding mechanism adapted to receive said blank after it is cut off from the said web and fold it into a receptacle.

LOUIS V. LUCIA. 20

DISCLAIMER

2,110,770.—*Louis V. Lucia*, West Hartford, Conn. MACHINE FOR AND METHOD OF MAKING PAPER CUPS. Patent dated March 8, 1938. Disclaimer filed September 5, 1941, by the assignee, *United States Envelope Company*.

Hereby enters this disclaimer to claim 8 of said patent.

[*Official Gazette September 30, 1941.*]

- comprising means for folding the side portion of said blank in overlapping position on the central portion thereof, means for creasing the said partly folded blank transversely at points spaced from the forward portion thereof, means for applying adhesive back of said transverse crease and folding means for folding the said forward portion upon said partly folded blank and into contact with said adhesive.
- 5 25. In a machine for producing paper containers of the character described from a web of paper, a mechanism for feeding the end of said web to said machine, means for cutting off the end of said web and thereby forming a container blank, 10 folding mechanism comprising means for partly folding the said blank by folding the side portions thereof in overlapping position upon the central portion of said blank on lines diverging from the axis of said central portion, means for forming a 15 crease upon the said partly folded blank on a line extending across the overlapping area of said side portions, and separate means for folding the said partly folded blank on said crease.
- 20 26. In a machine for making paper containers of the character described, the method for stacking the said containers which consists of delivering them substantially horizontally upon a surface and beneath the preceding containers, moving them forwardly on said surface to accumulate them thereon and thereby permit them to gradually rise to a substantially vertical position.
- 5 27. In a machine for converting a web of paper into receptacles of the character described, 10 the combination of means for feeding the said web lengthwise into said machine, a cutter for cutting off a section of said web, at the end thereof, and thereby forming a receptacle blank therefrom, means for holding said section against 15 movement while it is being cut off from said web, and folding mechanism adapted to receive said blank after it is cut off from the said web and fold it into a receptacle.
